UNITED STATES PATENT OFFICE.

ED WHITAKER, OF WATERLOO, IOWA, ASSIGNOR, BY DIRECT AND MESNE ASSIGNMENTS, OF ONE-THIRD TO IRETA L. ESCHER, OF CHICAGO, ILLINOIS.

VEHICLE HEADLIGHT.

Application filed March 3, 1924. Serial No. 696,627.

To all whom it may concern:

Be it known that I, Ed Whitaker, citizen of the United States, residing at Waterloo, in the county of Black Hawk and State of 5 Iowa, have invented certain new and useful Improvements in Vehicle Headlights, of which the following is a specification.

My invention relates to improvements in vehicle headlights, and the object of my 10 improvement is to supply particularly for use on motor-vehicles a headlight which is so constructed as to limit vertical light dispersion upwardly and downwardly while permitting sidewise light dispersion, and 15 arranged with cooperating opposite reflecting surfaces adapted to receive, conserve and direct light rays emitted from a source of illumination within the device, to the utmost advantage in the proper illumination of the 20 road before and to the sides of the vehicle, while preventing inconvenient glare to the drivers of vehicles approaching from an opposite direction.

This object I have accomplished by the 25 means which are hereinafter described and claimed and which are illustrated in the accompanying drawings, it being understood that changes in the precise embodiment of invention herein disclosed can be made without 30 in the scope of what is claimed without departing from the spirit of the invention.

In said drawings, Fig. 1 is a vertical central longitudinal section of my improved headlight and Fig. 2 is a front elevation 35 thereof. Fig. 3 is a vertical central longitudinal section of a modification of my improved headlight, and Fig. 4 is a front elevation thereof.

Referring first to Figs. 1 and 2, the 40 numeral 1 denotes a common form of lamp shell or housing within which is positioned a parabolic or concave reflector 2, mounted and secured therein in any desired way as by the clamping ring 3, the latter also serving 45 to secure in place on the lamp the transparent closure 4 together with upper and lower hoods or shutters 7 and 8, the former without and the latter within the lamp.

The upper hood or shutter 7 is preferably 50 a hollow spherical segment but may be otherwise shaped. The lower hood or shutter 8 is preferably a hollow conical frustum with its inner curvate edge approximately coaxial with the reflector 2, and the frustum 55 8 is also segmental and its upper horizontal

edge is positioned at a short distance below the horizontal lower edge of the hood 7 to give clearance therebetween at the sides of the lamp for sidewise uninterrupted light dispersion to thus illuminate the sides of the 60 road at both sides of the vehicle. The curvate edge 9 permits light to be directed ahead from a lamp 5 positioned at the focal point of the reflector 2, and the lamp is preferably mounted at 6 within the reflector 65 2 dependingly as shown to thus prevent cutting off any of the reflecting surface of the reflector directly behind the lamp. The reflector 2 is also slightly tilted forwardly and downwardly, being shaped with its 70 lower part elongated to have its forward edge in an approximate vertical transverse plane. This slight tilting results in directing reflected light rays slopingly toward the road in front of the vehicle at a determined 75 forward limit thus aiding in giving better illumination to the road in that area while measurably preventing upward light dispersion.

However, the forwardly projecting segmental hood 7 serves to limit the upward dispersion of light projection to a part below a certain height which height is below the height of the eyes of the driver of a vehicle approaching from an opposite direction, whereby a blinding glare is absolutely 80 prevented such as often leads to accidents when no such shutter is provided.

The lower hood or shutter 8 shuts off light 85 dispersion slightly as against upward dispersion of light from the lower part of the reflector 2. The inner surfaces of both hoods or shutters 7 and 8 are made reflecting, whereby the light from the lamp 5 otherwise shut off thereby is received and 90 conserved directively by reflecting the rays toward the reflector 2 thence to be projected forwardly as limited in direction by the hoods. As the hoods 7 and 8 are spaced 95 apart vertically, as will be seen in Fig. 2, 100 sidewise dispersion of light is not prevented, so that the light is directed sidewise from both sides of the vehicle.

Referring now to said Figs. 3 and 4, 105 illustrating a modification of my invention, the same shows a construction wherein the principle of my invention is preserved, as adapted in use to existing lamps. The housing 1, ring 3, glazing 4 and hoods or shutters 7 and 8 are the same as shown in 110

Fig. 1, but the reflector 2 of the parabolic type is the usual untilted kind having a central rearwardly rimmed opening at 11 which usually receives the shank 6 of a lamp 5. However, a smaller concave reflector 10, is positioned within the reflector 2, slightly tilted forwardly and downwardly with its axis below the axis of the reflector 2, and having a rearwardly directed hollow stem 12 which is passed through the rimmed opening 11 to project therefrom and with its projecting end exteriorly threaded to receive a socketed nut 14 which also incloses the rim 11 lockingly. A lamp 5 has its shank 6 mounting in the upper part of the reflector 10 with the lamp at the focal point thereof, the conductors 13 being carried between the reflectors and through an opening in the stem 12 and through the hollow of the latter 20 as shown.

The headlight shown in said Figs. 3 and 4 operates the same as the one shown in Figs. 1 and 2, and the tilting of the inner reflector 10 answers the same purpose as the tilting 25 of the reflector 2 of Fig. 1. This is a convenient method of installing the invention in the existing form of lamps.

Having described my invention, what I claim as new, and desire to secure by Letters 30 Patent, is:

1. In combination, differently sized nested concave reflectors, a concave reflecting screen projecting forwardly of the upper part of the reflectors to limit upward dispersion of 35 light therefrom, and a segmental truncated conical reflecting screen supported across the

forward lower part of said reflectors and apically directed interiorly to limit and concentrate downward dispersion of light therefrom, the adjacent transverse edges of 40 said screens being separated vertically to permit sidewise dispersion of light from the reflectors.

2. In combination, a concave reflector, a concave reflecting screen projecting across 45 the upper front part of the reflector, and a forwardly concaved screen extending into the reflector and positioned across its lower front part and having in its upper edge a recess located below the level of the lower 50 transverse edge of the upper screen to delimit light reflected through the recess from a source of illumination within the hollow of the reflector, said adjacent screen edges being vertically spaced. 55

3. In combination, a concave reflector, another and smaller concave reflector mounted therein and forwardly of its reflecting surface, the latter reflector being tilted to displace its focal center from the focal radius 60 of the former reflector to thereby direct light reflected from the latter reflector only obliquely downwardly forwardly, and reflecting screens mounted at the upper and lower parts of the first-mentioned reflector and spaced vertically to direct light side- 65 wise while limiting its dispersion upwardly and downwardly.

In testimony whereof he affixes his signature. 70

Waterloo, Iowa, February 29th, 1924.
ED WHITAKER.
